US0D1089263S

(12) **United States Design Patent** (10) **Patent No.:** **US D1,089,263 S**
Sanchez et al. (45) **Date of Patent:** **** Aug. 19, 2025**

(54) **DISPLAY SCREEN OR PORTION THEREOF
WITH A GRAPHICAL USER INTERFACE**

(71) Applicant: **IGT**, Las Vegas, NV (US)

(72) Inventors: **Gary Sanchez**, Reno, NV (US);
Darren Maya, Reno, NV (US); **Eric Holden**, South Lake Tahoe, CA (US);
Taisa Deaconu, Reno, NV (US)

(73) Assignee: **IGT**, Las Vegas, NV (US)

(**) Term: **15 Years**

(21) Appl. No.: **29/972,088**

(22) Filed: **Nov. 7, 2024**

Related U.S. Application Data

(63) Continuation of application No. 29/910,098, filed on Aug. 15, 2023, now Pat. No. Des. 1,055,089.

(57) CLAIM

The ornamental design for a display screen or portion thereof with a graphical user interface as shown and described.

DESCRIPTION

FIG. 1 is a front view of a display screen or portion thereof with a graphical user interface of one embodiment of our new design; and,

FIG. 2 is a front view of a display screen or portion thereof with a graphical user interface of another embodiment of our new design.

The dashed broken line perimeter in the drawings illustrate a display screen or portion thereof and forms no part of the claimed design. The remaining dashed broken lines in the drawings illustrate portions of the graphical user interface that form no part of the claimed design.

1 Claim, 2 Drawing Sheets

FIG. 1

FIG. 2
